UNITED STATES PATENT OFFICE

167,473

SPINDLE NOSE COLLET CHUCK

Peter Muller-Munk, Pittsburgh, Pa., assignor to
The Jacobs Manufacturing Company, West
Hartford, Conn., a corporation of Connecticut

Application February 9, 1951, Serial No. 14,153

Term of patent 14 years

(Cl. D54—14)

To all whom it may concern:

Be it known that I, Peter Muller-Munk, a citizen of the United States, residing at Pittsburgh, in the county of Allegheny and State of Pennsylvania, have invented a new, original, and ornamental Design for a Spindle Nose Collet Chuck, of which the following is a specification, reference being had to the accompanying drawing, forming part thereof.

Fig. 1 is a perspective view of a spindle nose collet chuck, showing my new design, and

Fig. 2 is a side elevation of the chuck illustrated in Fig. 1.

The side of the chuck illustrated in the accompanying drawing contains a centrally located seat and hole adapted to receive a chuck key. The other side of the chuck is like the side shown except that the centrally located seat for the key does not appear thereon.

I claim:

The ornamental design for a spindle nose collet chuck, as shown and described.

PETER MULLER-MUNK.
